(57) **CLAIM**

The ornamental design for furniture chest component, as shown and described.

DESCRIPTION

FIG. 1 is a front elevational view of my new design for a furniture chest component.

FIG. 2 is a right-side elevational view thereof, with the left-side elevational view being a mirror image thereof.

FIG. 3 is a rear elevational view thereof.

FIG. 4 is a top plan view thereof; and,

FIG. 5 is a bottom plan view thereof.

The broken line elements of the chest are solely to illustrate the environment of my design, and form no part of the claimed design.
